to American Safety Razor Corporation, Brooklyn, N. Y., a corporation of Virginia

Application July 27, 1951, Serial No. 16,055
Term of patent 14 years

(CL. D48—27)

To all whom it may concern:

Be it known that I, Herman George Treiss, a citizen of the United States, and a resident of Riverdale, county of Bronx, and State of New York, have invented a new, original, and ornamental Design for a Combined Cigarette Lighter and Letter Opener, of which the following is a specification, reference being had to the accompanying drawings, forming part thereof.

Fig. 1 is a perspective view of the front and left side of a combined cigarette lighter and letter opener, showing my new design;

Fig. 2 is a rear elevational view thereof;

Fig. 3 is a top plan view; and

Fig. 4 is a bottom view.

The dominant features of my design are shown in solid lines in the drawing.

I claim:

The ornamental design for a combined cigarette lighter and letter opener, as shown and described.

HERMAN GEORGE TREISS.
